UNITED STATES PATENT OFFICE.

HANS Z. NELSON, OF ALBERT LEA, MINNESOTA, ASSIGNOR TO AMERICAN GAS MACHINE COMPANY, OF ALBERT LEA, MINNESOTA, A CORPORATION OF MINNESOTA.

VALVE-ACTUATING DEVICE.

1,137,517.

Specification of Letters Patent. Patented Apr. 27, 1915.

Application filed May 1, 1912. Serial No. 694,540.

To all whom it may concern:

Be it known that I, HANS Z. NELSON, a citizen of the United States, and a resident of Albert Lea, in the county of Freeborn and State of Minnesota, have invented certain new and useful Improvements in Valve-Actuating Devices, of which the following, when taken in connection with the drawings accompanying and forming a part hereof, 10 is a full and complete description, sufficient to enable those skilled in the art to make, understand, and use the same.

This invention relates to valve actuating mechanism particularly adapted to close the 15 valve, at a determined time, which controls the supply of gasoline to vapor generating devices. And the principal objects of the invention are to obtain a device which is suitable for use in street lighting incan- 20 descent vapor lamps; and which may also be used in what are known as central generator incandescent lighting systems.

To accomplish the purposes sought by me I have embodied my invention in a construction which is simple, easily understood and operated, and which is not liable to get out 25 of order.

In said drawings Figure 1 is a front elevation of the device, and of a generating de- 30 vice, showing the casing of said generating device in section and showing the casing of the timing element of the device in side elevation. Fig. 2 is a rear elevation of said device. Fig. 3 is an isometric view of a 35 valve stem, the upper end of a lever, the lower end of an additional lever, both loosely mounted on said stem, and of a base which is rigidly mounted on said stem. Fig. 4 is a side elevation of the several parts which are 40 illustrated in Fig. 1, with said casing of the generating device in elevation. Fig. 5 is a horizontal section on line 5-5 of Fig. 4, viewed in the direction indicated by the arrows. Fig. 6 is a horizontal section on line 45 6-6 of Fig. 4, viewed in the direction indicated by the arrows. Fig. 7 is a rear elevation of said casing of the timing element and of the lever operated thereby, and Fig. 8 is a top plan view of a portion of said cas- 50 ing and lever.

Similar letters refer to similar parts throughout the several figures of the drawing.

Before describing the device embodying 55 this invention a brief description will be

given of a vapor generating device and accessories which are controlled by the device embodying this invention.

A is a casing, consisting of part a and part a' which is hinged to said part a by hinge a''.

a''' is the bottom of casing A.

B is a standard which is provided with horizontal member b, vertical member b', and base b''.

C are screws attaching base b'' to wall Z.

D is a filter tube, d is filtering material, d', is a screw threaded stem, d'' is a disk or piston on stem d', d''' is a cap on tube d and d'''' is a packing nut. When stem d' is 70 turned disk d'' is advanced and filtering material d is thereby compressed.

E is a gasoline supply pipe arranged to discharge into filter tube D.

N is a vapor generator and G is a con- 75 necting pipe between filter tube D and said generator N.

The device embodying this invention is constructed as follows: F is a valve which is provided with stem f.

H is a base which is rigidly secured to said stem f. Base H is provided with the arms h, h'.

I is a lever which is loosely mounted on said stem f. When said valve F is open the 85 lever I is necessarily raised into substantially the position thereof which is illustrated in Figs. 1, 2, 3 and 4, and resting against the abutment which is illustrated in said Fig. 4. Lever I is provided with the 90 horizontal part i, which is located or positioned between the arms h, h' of base H.

I' is a weight which is secured on lever I, in an adjusted position, by screw I''. When lever I is resting against the projection or abutment which is illustrated in Fig. 4, it is on or slightly over the center, of the axial line of stem f, and hence remains in said raised position.

J is a lever which is loosely mounted on 100 stem f, and said lever is provided with the part or portion j, which extends into the path of movement of part i of lever I, (see Figs. 2 and 3).

K is a bell crank which is pivotally mounted on fulcrum k.

K' is the shell or casing of the timing element of the device, (said timing element not being shown), and k is rigidly secured to said casing, (see Fig. 3). One end of lever J 110

is attached to the end of one of the arms of bell crank K, by loop *j'* and screw *h'*.

L is an arm or lever which is attached to bell crank K by pivot *h''*.

5 L' is a sharp edge on the under side of lever L, and L'' is a weight secured on said lever. M is the face of said shell K', and m is the key by means of which the spring (not shown) for actuating said timing element is wound. M' is a shaft or spindle of said timing element, and revolves once in an hour. Said shaft or spindle M' is provided with external screw threads, (see Fig. 8.)

15 M'' is a set bolt in arm or lever L. To set the timing device one end of set bolt M'' is brought into contact with the casing K' when arm or lever L is laid on shaft or spindle M', with the sharp edge L' in engagement with the external screw threads on said shaft; and hence, said bolt M'' is so adjusted in said lever L that the requisite number of revolutions of said shaft or spindle will occur before said lever L is discharged, from said shaft, (by the turning of said shaft). When said lever L is discharged from said shaft the weight L'' turns said lever J on its fulcrum *k*, thus moving crank K and turning lever J on stem *f* of the valve F. The turning of said lever J turns lever I, by part *j* of said lever J coming into contact with said lever I and forcing it around on stem *f*. After lever I has commenced to turn, and as it gains some 35 momentum, the horizontal part *i* thereof comes in contact with the arm *h* and forces the base H, (which is rigidly secured to stem *f*) to turn, carrying therewith said stem *f*; and said movement of stem *f* closes 40 the valve F in the ordinary way of closing needle and other valves by rotation of the stem thereof.

The several hereinbefore described elements comprised in the construction which 45 embodies my invention constitute means whereby, when a supply of gasoline is opened to the vapor generating device herein illustrated and described, the said supply is permitted to flow for a determined length 50 of time and is then shut off, automatically, by the operation of the device, at a time measured by the timing element of the device.

I claim—

55 1. The combination of a gasoline supply pipe, a valve and valve seat, to control the discharge of gasoline from said supply pipe, said valve provided with a stem, a base rigidly secured on said stem, a weighted lever and an additional lever, both loosely mounted to turn on said stem, said weighted lever normally held in inoperative position, means positioned between said weighted lever and said base whereby the turning of 60 65 the weighted lever turns the base and stem,

and said levers so related that the turning of the additional lever turns said weighted lever to permit the weight on said weighted lever to fall and thereby turn the base and valve stem, a timer provided with a screw threaded shaft, and an additional weighted lever mounted to be turned on its fulcrum by the fall of the weight on the weighted end thereof, said additional weighted lever adapted to normally rest on and be held in a raised position by said screw threaded shaft, and also adapted to be moved laterally off from said shaft by the turning thereof, and means connecting said additional weighted lever to said additional lever whereby the turning of said additional weighted lever turns said additional lever. 70 75 80

2. The combination with a valve body, valve and valve seat to control the discharge of gasoline, of a supply pipe attached to the said valve body, said valve provided with a stem, a base rigidly secured on said stem, arms carried by said base, a weighted lever and an additional lever both loosely mounted to turn on said stem, said weighted lever normally held in inoperative position, said arms and said base in the path of movement of said weighted lever, and said levers so related that turning of said additional lever turns said weighted lever to permit the weight of said weighted lever to fall and thereby move said arms and turn said base and valve stem, a timer provided with a screw-threaded shaft, an additional weighted lever adapted to turn on a fulcrum, and the weighted end thereof adapted to be moved laterally, and said weighted end adapted to rest on and to be supported by said screw-threaded shaft when said weighted end is in its normal or raised position, 95 100 105 whereby the rotation of said shaft moves said weighted end off therefrom to permit the said weighted end to fall and turn on its fulcrum, adjustable means to determine the particular screw threads on said shaft between which said additional weighted lever is placed, and means connecting said additional weighted lever to said additional lever, whereby the turning of said additional weighted lever turns said additional lever. 110 115

3. A valve and a valve seat arranged to co-act, said valve provided with a stem, in combination with a base rigidly secured on said stem, arms carried by said base, a weighted lever and an additional lever both loosely mounted on said stem, said weighted lever normally held in inoperative position, said arms in the path of movement of said weighted lever, and said levers so related that turning of said additional lever turns said weighted lever to a falling position, whereby the valve is operated, a screw threaded shaft, and a weighted lever normally resting on said shaft, said last named 120 125 130

weighted lever adapted to turn on its fulcrum and the part thereof on said shaft adapted to be moved laterally by said screw threads and discharged from said shaft by the turning thereof, and a connection between said last named weighted lever and said additional lever, whereby the discharge of said last named weighted

lever from said shaft permits the weighted end to fall, and turns said lever and said 10 additional lever.

HANS Z. NELSON.
